ATTACHING MEANS FOR CLOSURES

Hugo R. Hustad, New York, N. Y.

Application August 17, 1940, Serial No. 353,018

4 Claims. (Cl. 215—70)

My invention relates to means and devices for articulatively attaching a closure, or similar element, to an article to which it is adapted to be applied and removed at various times.

In the dispensing of liquids or other contents from bottles or other types of containers, it is desirable that the cap remain attached to the container to prevent possible loss after removal during the opening operation. It is also desirable that the so attached cap be automatically held in such a position that it will not interfere with normal discharge of contents from the container. For these purposes, I have provided by this invention an attaching device, and suitable co-ordinating means for rendering it operative, in combination with a container, or other suitable article, and a closure element therefor.

The invention is particularly useful in connection with closure caps for dispensing-types of containers and the like, and especially in connection with screw-threaded caps designed to screw over externally threaded necks which define dispensing orifices. The invention is not, however, restricted to any specific use or form, but may be utilized wherever, and in whatsoever specific forms, its generic attributes render it advantageous.

A primary object of the invention, therefore, is the production of a device of the type described that will retain the closure element in its open position when it has been swung back from the article which it normally closes.

An object is the production of a device of the type described which is simple in construction and operation, which is economical to produce, and which is applicable to a wide variety of specific instances of use.

An outstanding feature of the invention resides in the provision of a resilient portion for the attaching element per se, and in the association, with the closure element, of projecting means which cause the resilient portion of the attaching element to flex outwardly when the closure element is swung into open position, and to press the closure element—in its open position—tightly against the neck or corresponding portion of the article, so that it remains open, as, for instance, during a pouring operation, until manually swung back into closed position once again.

Further features and objects of the invention will be obvious from the following detailed description and the accompanying drawing.

In the drawing:

Fig. 1 represents a side elevation of a flask or

bottle closed by a cap which is attached thereto by a preferred embodiment of the invention;

Fig. 2 represents a rear elevation of the structure illustrated in Fig. 1;

Fig. 3 represents a side elevation of the structure illustrated in Fig. 1, with cap in retained open position, and the flask tipped in a pouring operation; the bottom portion of the flask is broken away for convenience of illustration;

Fig. 4 represents an enlarged fragmentary view in vertical section of the neck portion of the flask of Fig. 1 with cap positioned thereover preparatory to being screwed down into initial placement and into engagement with the attaching device;

Fig. 5 is a view similar to that of Fig. 4, but illustrating the cap as screwed down on the neck, tightly closing the flask and cooperating with the attaching device;

Fig. 6 is a view similar to those of Figs. 4 and 5 but illustrating the cap in a position similar to that of Fig. 4, although, here, actually in engagement with the attaching device; the cap is also indicated by dotted lines as it appears in its completely open but attached position, and also in an intermediate position.

Fig. 7 represents a view in perspective of the attaching element per se.

The invention is illustrated in a preferred form, and, in this specific instance of use, in association with a dispensing type of container having an externally threaded neck and a screw-threaded cap for application thereto. The generic characteristics of the invention, however, as set forth hereinbefore and as will appear hereinafter, may be embodied in a great many different forms for a variety of uses.

The flask or bottle 10 of the illustrated embodiment has a neck 11, externally threaded as at 11a, see especially Fig. 3. The neck 11 defines a dispensing orifice 12, see Figs. 4, 5 and 6.

The neck 11 of the flask 10 is provided with a circumferential slideway 11b, defined at the base thereof by a circumferential bead 11c which is spaced upwardly a suitable distance from the juncture of the neck 11 with the body proper of the flask.

The purpose of the slideway 11b is to receive an independent attaching element, hereinafter described, in such a manner that the attaching element can rotate freely about the neck, and the purpose of the bead 11c is to function as a stop for limiting movement of the attaching element lengthwise of the neck 11, that is, for confining movement of the attaching element to the slide-

way. Bearing this in mind, other arrangements and forms of the described members will be apparent to those skilled in the art, and may be utilized without departing from the generic spirit and scope of the invention.

The flask 10 may be of any suitable material such as glass, metal, a plastic, etc., and the neck 11 thereof, together with the external threads 11a, the circumferential slideway 11b, and the circumferential bead 11c are preferably integral with the body proper of the flask, all being pressed, molded, or otherwise processed to final shape in any appropriate and well known manner, as found desirable.

In this instance, a screw-threaded cap 13 forms the closure element for the flask 10. As is customary, it is provided with internal threading 13a for mating with the external threading 11a of the neck of the bottle. It may be formed of any suitable material, being advantageously a molded plastic.

Pursuant to a preferred form of the invention, the cap 13 is provided with a pair of mutually spaced, projecting cam members 13b and 13c which serve to secure a transverse pin 14. The pin 14 serves to engage the hooked upper end 15a of resilient arm 15 of the attaching element, this element being illustrated per se and indicated 16 in Fig. 7.

The attaching element is preferably resilient in its entirety and formed for easy application to the container with which it is to be associated. In the case of the attaching element 16, which is designed for easy removable application to the neck 11 of the container 10, the entire element is resilient and is formed from a metal stamping.

A collar 17 is provided for the attaching element 16, the same being adjustable to a limited extent by reason of the entrance gap 18 formed therein. The resilient linkage arm portion 15 of the attaching element preferably extends in a plane which is substantially perpendicular to the plane in which the collar 17 lies. It preferably goes abruptly outwardly adjacent its joinder with the collar portion 17, as is indicated at 15b, for accommodating the circumferential bead 11c of the neck 11. The hooked upper end 15a, of the arm portion 15, has a sufficiently long lip portion 15a' to insure proper entrance of the pin 14 into the cradle of the hook, and its retention thereby, during temporary removal and replacement of the cap 13. Also, the hooked portion 15a has a crook 15a'' therein which positively retains pin 14 as the cap is swung back through the intermediate position, indicated by dotted lines in Fig. 6, into the completely open position, also indicated by dotted lines in Fig. 6, and which positively prevents pin 14 from slipping out of the cradle of the hooked portion 15a in the opened rest position of the cap.

Generically speaking, the function of the crook 15a'' may be effectively taken care of by other structural means, that is, by any arrangement of means which prevents disengagement of the pin 14, or its functional equivalent, from the hooked upper end 15a of resilient arm 15, or its functional equivalent. For instance, the hooked upper end, 15a, might be made without a crook, but with a small external projection adapted to snap into a small coordinating recess appropriately provided in the outer surface of cap 13 between projecting cam members 13b and 13c, when the cap is swung back.

After the collar portion 17 of the attaching element 16 has been sprung into place about the

slideway 11b of the bottle, in the assembling of the cap 13 and the bottle 10, the resilient arm 15 is flexed outwardly, either manually or by the action of the cap itself, so that, when the cap is

5 screwed downwardly on the neck, the attaching element in its entirety rotates about the neck, and, as the cap descends, the resilient arm 15 springs back into position, see Fig. 5, to insure engagement of pin 14 with the hooked upper portion 15a thereof during a subsequent removal of the cap for opening the bottle, see Figs. 5 and 6.

In removing the cap 13 in order to uncover the opening 12 in the neck of the bottle, the cap is 15 swung back from the neck on pin 14, which functions as a pivot or pintle rotating within the cradle of the hooked upper end 15a of the resilient arm 15, see Fig. 6.

In order to insure the automatic retention of the closure element in its open position, the 20 projecting cam members thereof are formed in such manner that the body proper of the closure element will be displaced outwardly from the container, carrying with it the pin or other device which forms the pivot or pintle on which the closure element swings, and flexing the resilient arm of the attaching element outwardly. They are formed also in such manner as to abut against the outside surface of the container, holding the closure element substantially inverted at the 25 limit of its outward swing and free and clear of the opening in the container.

The projecting cam members 13b and 13c are, to the above end, formed substantially rectangular as illustrated, extending from the bottom of the cap to substantially the top thereof. The pin 14 is spaced upwardly from the bottoms thereof a distance sufficient to permit adequate leverage in flexing the resilient arm 15 outwardly from the neck, the fulcrum, in this instance, being provided by the bottom outer corners 13b' and 13c' bearing against the outer surface of the neck 11 of the bottle. When the cap 13 has completed its outward swing, the outer longitudinal edges of the projecting members 13b and 13c will rest against the neck 11, as is illustrated in Fig. 3, while the pin 14 fits snugly in the crook 15a'' of resilient arm 15. Thus, the bottle may be properly turned into pouring position without danger of the attached cap 13 assuming such position as would interfere with the free flow of contents from the bottle during the pouring operation.

The projecting cam members 13b and 13c may be given a variety of forms without impairing their functional effectiveness. In adopting other forms, however, it is important to keep in mind that they must be so proportioned and positioned as to serve as fulcrums for flexing the resilient arm of the attaching element outwardly, and as rests for maintaining the resilient arm 15 in its outwardly flexed position so long as the cap is in its open condition.

Whereas this invention has been illustrated and described with respect to a specific embodiment thereof, it is to be clearly understood that a great 65 number of changes may be made without departing from the generic spirit and scope of the invention as described herein and in the claims that follow.

I claim:

1. In combination with an article having a neck member defining an opening, a removable cap for closing said opening, said cap having spaced walls extending substantially in parallelism radially outwardly therefrom and a pintle secured to one of said walls and extending toward

the other of said walls; and means for articulatively securing said cap to said article, comprising a collar rotatably attached to said neck member, a resilient arm extending upwardly from said collar and biased outwardly from said neck, the free end of said arm being directed downwardly to provide an open-ended hook disposed between the spaced walls of said cap and adapted to engage the pintle to permit swinging of said cap outwardly about said pintle, the outer edges of 10 said spaced walls providing cam surfaces engageable with the wall of said neck to flex said resilient arm and thereby hold said cap in its said outwardly swung position.

2. In combination, an article; a cover for said article; resilient linkage means; means attaching said resilient linkage means to said article; a pintle secured to said cover and arranged to engage said resilient linkage means during the removal of said cover from said article thereby articulatively attaching said cover to said article; and cam means secured to said cover adjacent said pintle, said cam means being adapted to cause said pintle to flex said resilient linkage means when said cover is swung back from said article and to thereby retain said cover in its swung-back position until forcibly removed therefrom, wherein the resilient linkage means comprises a resilient arm having a hooked terminus; wherein the cam means comprise a pair of spaced cam elements; and wherein the linkage engaging means comprises a pintle element extending between and having its ends secured in the said cam elements, the said pintle being arranged to engage the said hooked terminus of the resilient arm.

3. In combination, an article; a cover for said article; resilient linkage means; means attaching said resilient linkage means to said article; a pintle secured to said cover and arranged to engage said resilient linkage means during the removal of said cover from said article thereby articulatively attaching said cover to said ar-

15 ticle; and cam means secured to said cover adjacent said pintle, said cam means being adapted to cause said pintle to flex said resilient linkage means when said cover is swung back from said article and to thereby retain said cover in its 20 swung-back position until forcibly removed therefrom, wherein the resilient linkage means comprises a resilient arm having a hooked terminus; wherein the cam means comprise a pair of spaced cam elements; and wherein the linkage engaging means comprises a pintle element extending between and having its ends secured in the said cam elements, the said pintle being arranged to engage the said hooked terminus of the resilient arm; and wherein there is provided means for retaining the pintle within the said hooked terminus of the resilient arm when the cover is in its 25 swung-back position.

4. In combination, a container having an externally threaded neck defining a dispensing orifice; an internally threaded cap adapted to screw onto the neck of said container; a circumferential slideway formed adjacent the base of the neck of said container; a collar rotatably mounted upon the said slideway; a resilient arm extending from the said collar toward the dispensing orifice of the neck of said container, said resilient arm having a hooked terminus; a pair of spaced cam elements extending from the side of said cap, externally thereof; a pintle element extending between and having its ends secured in said cam elements, said pintle element being arranged to engage the hooked terminus of said resilient arm during the removal of said cap from 30 the neck of said container, thereby articulatively attaching said cap to said container, and said cam elements being adapted to cause said pintle element to flex said resilient arm when said cap is swung back from said container and to thereby 35 retain said cap in its swung-back position until 40 forcibly moved therefrom.

HUGO R. HUSTAD.
